UNITED STATES PATENT OFFICE.

NELSON J. FINWALL, OF EWING, NEBRASKA.

FARM-GATE.

1,101,793.

Specification of Letters Patent. Patented June 30, 1914.

Application filed February 18, 1914. Serial No. 819,420.

To all whom it may concern:

Be it known that I, NELSON J. FINWALL, citizen of the United States, residing at Ewing, in the county of Holt and State of Nebraska, have invented certain new and useful Improvements in Farm-Gates, of which the following is a specification.

The present invention relates to certain new and useful improvements in farm gates, 10 and has for its primary object to provide a gate which embodies novel features of construction whereby it can be readily opened and closed by a person riding upon a vehicle or mounted upon a horse, without the 15 necessity of dismounting.

A further object of the invention is to provide a gate of this character which is comparatively simple and inexpensive in its construction, which swings in a vertical 20 plane and occupies but a small amount of space, which can be easily and quickly swung into either an open or a closed position, and which is positive and reliable in its operation.

25 With these and other objects in view, the invention consists in certain novel combinations and arrangements of the parts as will more fully appear as the description proceeds, the novel features thereof being 30 pointed out in the appended claims.

For a full understanding of the invention, reference is to be had to the following description and accompanying drawing, in which:—

35 Figure 1 is a side elevation of a farm gate constructed in accordance with the invention, the gate being shown by full lines in a closed position and by dotted lines in an open position, and portions being broken 40 away. Fig. 2 is a top plan view of a gate constructed in accordance with the invention, portions of the operating levers being broken away. Fig. 3 is a transverse vertical sectional view through the gate on the line 3—3 45 of Fig. 1, portions being broken away and shown in section. Fig. 4 is a detail view of the pivoted end of the gate, showing the manner of connecting the operating cable thereto. Fig. 5 is an end view of the gate, 50 the upper ends of the standards being broken away. Fig. 6 is a detail view of the pivot end of the gate, showing the position of the operating cables when the gate is swung upwardly into an open position. Fig. 7 is a 55 detail view showing a slight modification in

which the inner ends of the operating levers are connected by link hangers.

Corresponding and like parts are referred to in the following description and indicated in all the views of the drawing by the same 60 reference characters.

Specifically describing the present embodiment of the invention, the numeral 1 designates the body portion of the gate which may be built up from a number of bars in 65 the conventional manner. The pivot end of the gate is formed with a solid plate 2 which provides a vertical turn table. A hub 3 is provided at substantially the central portion of the plate or turn-table 2, the edge 2^a of 70 the plate 2 at the extreme end of the gate being substantially semi-circular and having the hub 3 as its center of curvature. The plate or vertical turntable 2 is received loosely between the lower ends of a pair of 75 spaced vertical standards 4, the said standards being connected by a transverse bolt 5 which passes through the hub 3 and upon which the plate 2 is mounted so as to turn in a vertical plane.

An operating lever 6 is pivotally mounted upon the upper end of each of the standards 4, the inner ends of the operating levers having a hinged connection 7 so that the two 80 levers will swing in unison, while the outer ends of the operating levers are provided with pendent cables or chains 8 providing handles which can be grasped to open or close the gate, as may be desired. The pivotal connection between the operating levers 90 and the standards 4 is necessarily loose and for this purpose slots 9 are provided in the operating levers through which the pivot pins 10 of the standards 4 pass. A spring 30 is connected to the inner end of one of the 95 operating levers 6 and normally tends to pull downwardly upon the inner end of the lever to hold the said levers normally in operative position. As soon as the operating levers 6 are released, after manipulating 100 the same to open or close the gate, the spring 30 serves to return them to normal position.

An operating cable 11 has the upper end thereof connected to the inner ends of the two operating levers 6, the lower end of the 105 operating cable being connected to a pair of branch cables 12 and 13, while the intermediate portion of the cable passes loosely through suitable guides 14 upon one of the standards 4. The two branch cables 12 and 110

13 are connected to the pivot plate or turntable 2 of the gate at the points 15 and 16 respectively, the said points being located upon imaginary lines radiating from the center of the hub 3 and subtending an angle of substantially 90°. When the gate is in a closed position, the point 15 is located directly over the pivot rod 5 and the point 16 on the side thereof toward the gate 1 (see Fig. 4), while when the gate is in an open position the point 16 is directly over the pivot rod 5 and the point 15 on the side thereof remote from the gate opening.

Assuming the gate 1 to be in a closed position, a downward pull upon one of the handles 8 will swing the outer ends of the operating levers 6 down and move the inner ends thereof up, thereby imparting an upward pull to the operating cable 11. With the two branch cables 12 and 13 in the position indicated by Fig. 4, it will be obvious that the entire pull upon the operating cable 11 will be imparted through the branch cable 13 to the point 16 upon the pivot plate 2 so as to swing the gate upwardly. The handle 8 will be released before the branch cable 12 also becomes taut, and the momentum of the gate will then swing the same upwardly into a completely open position. When the gate is open, the relation of the branch cables 12 and 13 to the main cable 11 is reversed, so that when one of the operating levers 6 is again pulled downwardly, the tension of the cable 11 is imparted through the branch cable 12 to the point 15. This starts the gate in its downward swinging movement and the operating lever 6 is released before the branch cable 13 becomes taut, the momentum of the gate being then sufficient to complete the closing movement thereof. In order to facilitate the opening and closing of the gate a series of weights 17, 18 and 19 are applied thereto in such a manner as to balance the same as nearly as possible. Upon the initial upward swinging movement of the gate the weight 18 is shifted from one side of the pivot bolt 5 to the opposite side thereof so as to assist in opening the gate, while upon the initial closing movement of the gate the weight 19 is shifted from one side of the pivot bolt 5 to the opposite side thereof so as to assist in closing the gate.

Latch means is also provided for locking the gate positively in an open and closed position so as to prevent accidental opening and closing of the gate, the said latch means being automatically released by the gate operating mechanism preparatory to swinging the gate into either an open or a closed position. The latch lever 20 is shown as horizontally disposed and passing through one of the standards 4, the middle portion of the lever being pivotally mounted upon the standard at 21. The nose of the latch lever

is adapted to engage either one of a pair of notched keepers 22 and 22^a applied to the pivot plate 2 of the gate. The rear end of the latch lever 20 is engaged by a spring 23 which normally tends to hold the latch in an operative position and the sides of the notched keepers 22 and 22^a are inclined or beveled so as to engage the nose of the latch lever and lift the same against the action of the spring 23 preparatory to letting it drop into the notch. The inner end of the latch lever 20 has a yielding or spring connection, as indicated at 24 with the main operating cable 11. The parts are so connected to the cable 11 relatively to each other that the initial upward movement of the said cable operates to lift the nose of the latch lever 20 from the keeper 22 or 22^a so as to unlock the gate preparatory to swinging the same into either an open or a closed position. When the gate reaches its final position, either open or closed, the nose of the latch lever 20 engages the inclined sides of the respective keeper and is lifted thereby against the action of the spring 23 preparatory to dropping into the notch of the keeper and locking the gate against further swinging movement in either direction.

When in a closed position the outer or free end of the gate 1 may be received between a pair of spaced posts 25 so as to be held against lateral swinging movement and effectively reinforced so as to resist the efforts of stock or the like to open or break the gate.

In order to explain the operation of the gate, let it be assumed that the gate is in a closed position, as shown by Fig. 1. The operator desiring to open the gate pulls downwardly upon one of the chains 8 and thereby manipulates the operating levers 6 to pull upwardly upon the main operating cable 11. This operates through the spring 24 to release the latch lever 20 from engagement with the notched keeper 22 and at the same time produces tension in the branch cable 13, the other branch cable 12 being loose. This imparts an initial upward swinging movement to the gate and the operating lever 6 is released before the branch cable 12 becomes taut, the momentum of the gate being then sufficient to swing it upwardly into an open position. When the gate reaches an open position, the latch 20 engages the notched keeper 22^a so as to lock it against accidental closing movement. In order to close the gate, it is merely necessary to again manipulate one of the operating levers 6 so as to pull upwardly upon the main operating cable 11. This operates as in the previous instance through the spring 24 to release the latch 20 from the notched keeper 22^a and to produce tension in the branch cable 12, the branch cable 13 remaining loose. The gate is thus swung into a

closed position, the latch 20 engaging the notched keeper 22 to lock the gate against accidental opening as soon as it is completely closed.

5 A slight modification is shown by Fig. 7, in which the inner ends of the operating levers 6 are pivotally connected to hangers 26, the lower ends of the hangers being pivotally connected at 27 and having the upper 10 end of the operating cable 11 connected thereto. The spring 29 which normally holds the levers 6 yieldably in operative position is also connected to these hangers 26. This construction eliminates the necessity 15 for providing the levers 6 with the slots 9, as in the previous instance, and provides an effective manner of connecting the levers to the operating cable 11 and spring 29.

Having thus described the invention, what 20 I claim as new and desire to secure by Letters Patent, is:—

1. A farm gate including a standard, a gate provided at one end thereof with a pivot plate, a pivotal connection between the 25 pivot plate and the standard whereby the gate can swing upwardly in a vertical plane, an operating lever mounted upon the standard, a main cable connected to the operating lever, a pair of branch cables connecting the 30 main cable to the pivot plate at points substantially 90° apart relative to the pivotal connection between the pivot plate and the standard, a latch lever mounted upon the standard, a pair of keepers arranged upon 35 the pivot plate substantially 90° apart with respect to the pivot center thereof and adapted to alternately engage the nose of the latch lever to lock the gate in open and closed positions, and an operative connection

between the latch lever and the main cable 40 for releasing the latch preparatory to swinging the gate when the operating lever is manipulated.

2. A farm gate including a standard, a gate provided at one end thereof with a pivot 45 plate, a pivotal connection between the pivot plate and the standard whereby the gate is adapted to swing in a vertical plane, an operating lever pivotally mounted between its ends upon the upper end of the standard, 50 a handle connected to one end of the operating lever, a main cable connected to the other end of the operating lever, a spring normally holding the operating lever in operative position, a pair of branch cables connecting the main cable to the pivot plate at points substantially 90° apart relative to the pivot center thereof, said branch cables being brought alternately into action to open 55 and close the gate as the main lever is successively actuated, a latch lever mounted upon the standard, a pair of keepers applied to the pivot plate at points substantially 90° apart relative to the pivot center thereof and adapted to alternately engage the nose of 60 the latch lever to lock the gate in an open or a closed position, and a yielding connection between the latch lever and the main cable for automatically releasing the latch lever preparatory to swinging the gate when 65 the operating lever is manipulated.

In testimony whereof I affix my signature in presence of two witnesses.
